Inventor Alphonse Lafayee

UNITED STATES PATENT OFFICE.

ALPHONSE LAFARGUE, OF KENSINGTON, COUNTY OF MIDDLESEX, ENGLAND.

HYDRAULIC HOISTING MACHINERY.

SPECIFICATION forming part of Letters Patent No. 259,175, dated June 6, 1882.

Application filed May 11, 1881. (No model.) Patented in England May 25, 1877, No. 2,045, and May 25, 1880, No. 2,122.

To all whom it may concern:

Be it known that I, ALPHONSE LAFARGUE, of Kensington, in the county of Middlesex, England, have invented certain new and useful Improvements in Hydraulic Hoisting Machinery, of which the following is a specification.

Certain features of this application are embraced in British Letters Patent No. 2,122, granted to me May 25, 1880, and in British Letters Patent No. 2,045, granted to me and Claude Martin, May 25, 1877.

My invention relates to a crane comprising a cylinder which forms the main pillar or column of the crane, and a piston fitting in said cylinder and attached to an extensible column or pillar which carries a sheave, and the raising of which effects the lifting. The aforesaid piston has its two sides of different area; and the invention consists in the combination, with the aforesaid cylinder and piston, of a novel arrangement of valves, hereinafter particularly described and claimed, and which may be adjusted to cause the water-pressure to act only on the side of the piston which is of larger area when a heavy load is to be lifted, or to cause pressure to act on both sides of the piston when a light load is to be lifted, in which latter case the lifting-power will be proportionate to the difference in area between the two sides of the piston.

In the accompanying drawings, Figure 1 represents a central vertical section of a crane embodying my improvements, and Fig. 2 represents a partly-sectional elevation at right angles to Fig. 1.

Similar letters of reference designate corresponding parts in both the figures.

b designates the lower or base portion of the central column or pillar of the crane, which is fitted in a stop-bearing at *b'* and a bearing, *b''*, in the deck *B*. At the upper end of the section or portion *b* is a valve box or chamber, *b³*, and upon the top thereof is mounted a cylinder, *a*, which forms the upper portion of the crane column or pillar. Within the cylinder *a* is fitted a piston, *e*, from which projects upward a ram or an extensible column or pillar, *a'*, which works through a stuffing-box, *a²*, in the upper end of the cylinder *a*, and is actuated

by the piston *e*. The upper end of the extensible column or pillar *a'* is bifurcated or forked, and in the said end is fitted a sheave, *E*.

F designates the boom or jib of the crane, which is provided with a roller, *s*, bearing upon a circular track around the column *b*, and the outer end of which is supported by a suspension-brace or tie-rod, *s'*, extending from the top of the cylinder *a* to the outer end of the boom or jib *F*.

G G' designate two tackle-blocks or pulleys—the former pivoted in the boom or jib *F* and the latter attached to the end of a cable, *t*, which passes around the sheave *E* and has its other end secured at *e'*. The cable *t'*, which is roved upon the tackle-blocks *G G'*, passes outward and over a pulley or sheave, *t²*, at the end of the boom or jib, and thence downward to a hook or suspension device, *t³*.

From the above it will be clearly seen that the raising of the piston *e* and sheave *E* will raise the tackle-block *G'* and effect the lifting of goods, while the lowering of said piston and sheave will have the opposite effect.

I will now describe the mechanism for controlling the admission of water to the cylinder *a*.

Water or other liquid is supplied through a pipe, *j*, from a pump or other source of supply to the bottom of the column or pillar *b*, and thence passes upward through a pipe, *c*, to a valve, *d*, the plug of which may be oscillated by a lever, *f*. This valve communicates by means of a pipe, *d'*, with the cylinder *a* below the piston *e*, and by means of a pipe, *j'*, and passage *j²* with said cylinder above the piston *e*. In the pipe *j'* is a valve or cock, *h*, which may be operated by a lever, *h'*, to permit the liquid to pass directly through it, or to cut off communication between the valve *d* and the passage *j²* and permit the water to be discharged from above the piston *e*, through the exhaust-pipe *i*, into the pillar *b*, from which the waste liquid is discharged through a pipe, *g'*.

When a light weight is to be lifted the cock *h* is adjusted so as to permit of the free passage of water above the piston *e*, and the valve *d* being properly adjusted, the liquid under pressure will pass to the cylinder *a* above and below the piston *e*, and the effective pow-

er exerted will be proportioned to the difference in area between the two sides of the piston *e*, adapting the crane for light weights. If, however, the cock *h* be adjusted to permit 5 the liquid from above the piston *e* to be exhausted through the pipe *i*, the valve *h* may be adjusted so as to supply liquid only below the piston *e* through the pipe *d'*, and the power exerted will be proportioned to the area of the 10 under side of the piston *e*, adapting the crane for heavy weights. In lowering, the cock *d* is adjusted to permit of the liquid being discharged from below piston *e* through the pipe *g*.

The cylinder *a* and the piston *e*, the two sides 15 of which are of different area, might be employed in other hoisting or lifting apparatus than that represented.

What I claim as my invention is—

1. The combination, with the cylinder *a* and 20 piston *e*, having its two sides of different area, of the valve *d*, pipes leading therefrom to said cylinder on both sides of said piston, and the

valve *h* in the pipe leading to the cylinder on the side of the piston which is of smaller area, and adapted to be closed to allow liquid to escape 25 from the cylinder on that side of the piston, or opened to permit the pressure to act on both sides of said piston, substantially as specified.

2. The combination of the cylinder *a*, the piston *e*, the extensible column *a'*, the sheave 30 *E*, carried thereby, the valves *d* *h*, the boom or jib *F*, adapted to be adjusted around said column, the block *G* in the boom or jib, the cable *t*, passing over the sheave *E*, the movable block *G'*, suspended by said cable, and the cable *t'*, 35 rove upon the blocks *G* *G'*, all substantially as specified.

ALPHONSE LAFARGUE.
